UNITED STATES PATENT OFFICE.

WILLY SARFERT, OF DRESDEN, AND FRIEDRICH HÄBERLE, OF ZSCHIEREN, NEAR DRESDEN, GERMANY, ASSIGNORS TO SACHSENWERK, LICHT- UND KRAFT- AKTIEN- GESELLSCHAFT, OF NIEDERSEDLITZ N/DRESDEN, SAXONY, GERMANY.

OIL-INSULATED TRANSFORMER.

Application filed December 19, 1923, Serial No. 681,466, and in Germany June 6, 1923.

This invention relates to an improvement in oil insulated transformers or like electrical apparatus. Heretofore, in apparatus of this kind, in order to maintain the apparatus filled with an insulating fluid and to provide for the expansion and contraction thereof, independent of extraneous compartments and chambers have been employed in some instances, while in other instances to insure the upper portion of the chamber being filled an auxiliary chamber has been employed in which a gas under pressure has been used for this purpose.

The object of our invention is to provide a simple means for preventing the accumulation of dangerous or noxious gases in the insulating chamber compartment of an apparatus of the type to which the invention relates by the use of a bushing having a sufficiently large bore therein to permit of the expansion and contraction of the insulating liquid or fluid under atmospheric pressure, as will be hereinafter more particularly described.

25 In the drawing:

Fig. 1 is a sectional elevation of a transformer made in accordance with our invention, and

30 Fig. 2 is a similar view showing another form of transformer.

Referring to the drawing and particularly to Fig. 1, in carrying out our invention we employ a suitable receptacle comprising a vessel 10 adapted to receive and contain a 35 transformer 11 or other similar apparatus and to be filled with oil or other similar liquid insulating material as indicated at 12. This vessel is provided with a cover 13 which may be attached and secured thereto in any suitable manner.

40 Passing through the cover 13 there are bushings 14 and 15. For this purpose the cover is provided with apertured bosses 16 and 17 respectively, and the form of the bushings exteriorly and that of the apertures in the bosses after passing through the apertures extend at their inner ends an appreciable distance into the receptacle 10 and are secured by any suitable means in the cover 45 of the apparatus. These bushings 14 and 15 are provided respectively with bores 18 and 19 of sufficient diameter to provide an appreciable chamber within the bushing. The

chamber in each bore is sufficiently large to permit the insulating liquid to rise therein 55 and to provide for the expansion and contraction of the liquid due to the rise and fall in the temperature of the apparatus and this expansion and contraction takes place under atmospheric pressure due to the fact that 60 the outer ends of the bushings are open to the atmosphere by way of ports 18' 19'. The leads 20 and 21 from the coils of the transformer, as will be understood, and as is illustrated in this figure of the drawing, pass 65 through the bushings and may be connected to terminals provided for this purpose on the outer ends of the bushings.

A somewhat similar transformer of a different type, however, is illustrated in Fig. 2. 70 In this structure the vessel or receptacle is designated at 22. This is provided with a cover 23 suitably connected thereto and to which the core 24 of the transformer is suitably secured. The bushing in this structure is indicated at 25 and is mounted in a flange 26 provided for this purpose in the cover 23. The winding of the core of the transformer in this structure is indicated at 27 and the ends thereof as indicated at 28 80 and 29 are passed through the chamber 30 in the bushing 25, this chamber 30 being of sufficient extent to permit the oil or other liquid insulating material contained in the receptacle 22 to expand and contract there- 85 in under the changes of temperature in a manner similar to that hereinbefore described in the form of the invention shown in Fig. 1, the outer end of the bushing 25 being open to the atmosphere so that this 90 expansion and contraction takes place under atmospheric pressure.

We claim as our invention:

1. In an apparatus of the class described, a casing, an insulating liquid filling the 95 casing, and a hollow open ended bushing extending upwardly from the casing and downwardly into the casing and adapted to provide for the expansion and contraction of the insulating liquid within the casing 100 under atmospheric conditions.

2. In an apparatus of the class described, a casing, a transformer within the casing, an insulating liquid filling the casing, and a bushing extending upwardly from the cas- 105 ing and downwardly into the liquid within

the casing, the said bushing having a bore of sufficient diameter to provide a chamber of sufficient capacity to permit the insulating liquid to expand and contract under atmospheric conditions due to the rise and fall of the temperature of the apparatus.

3. In an apparatus of the class described, a casing, an insulating liquid filling the casing, hollow open ended bushings extending upwardly on the casing and downwardly into the casing and adapted to provide for the expansion and contraction of the insulating liquid within the casing under atmospheric conditions, and a transformer submerged in the insulating liquid within the casing and having the leads of its windings passing through the said bushings and connected to terminals at the outer ends thereof.
- 20 4. In an apparatus of the class described,

a casing comprising a body and a cover therefor, an insulating liquid filling the casing, bushings extending upwardly from the casing and downwardly into the liquid within the casing, the said bushings each having a bore of sufficient diameter to provide a chamber of sufficient capacity to permit the insulating liquid to expand and contract under atmospheric conditions due to the rise and fall of the temperature of the apparatus, and a transformer secured to the said cover and submerged in the insulating liquid in the casing and having the leads of its windings passing through the said bushings and connected to terminals at the outer ends thereof.

In testimony, that we claim the foregoing as our invention we have signed our names.

WILLY SARFERT.

FRIEDRICH HÄBERLE.
